UNITED STATES PATENT OFFICE.

WILLIAM SHAKESPEARE, JR., OF KALAMAZOO, MICHIGAN.

FRAME FOR FISHING-REELS.

No. 801,479.

Specification of Letters Patent.

Patented Oct. 10, 1905.

Application filed August 18, 1902. Serial No. 120,027.

To all whom it may concern:

Be it known that I, WILLIAM SHAKESPEARE, Jr., a citizen of the United States, residing at the city of Kalamazoo, in the county of Kalamazoo and State of Michigan, have invented certain new and useful Improvements in Frames for Fishing-Reels, of which the following is a specification.

This invention relates to improvements in fishing-reels, and more particularly to improvements in the frame construction thereof.

Fishing-reels as ordinarily constructed are made with quite heavy ends in order to provide the necessary size and strength, or else when made of rubber or similar material they have been made large and cumbersome, and when so constructed are liable to serious warping and damages by abrasion, and when formed by drawing the metal must be comparatively soft and is liable to become twisted or bent or jammed by use.

It is the object of this invention to provide a construction of reel-frame which is of sufficient size and possesses the necessary rigidity and yet is composite in its construction, securing the advantages of both classes of material.

A further object is to provide an improved construction of reel-frame in which the parts can be readily assembled or taken apart, in which the likelihood of friction on the spool is avoided, and in which the spool can be readily removed without disassembling the entire reel.

35 A further object is to provide a construction of frame in which the spool can run freely and in which the flanges will be properly embraced, so that a close fitting of the spool parts is largely avoided.

40 Another object is to provide an improved construction of crank-handle for a fishing-reel.

The various objects of this invention are accomplished by the devices and means described in this specification.

45 The invention is clearly defined, and pointed out in the claims.

A structure embodying the features of the invention is clearly illustrated in the accompanying drawings, forming a part of this 50 specification, in which—

Figure 1 is a side elevation view of a reel embodying the features of this invention. Fig. 2 is a detail sectional view taken on the irregular line 2 2 of Fig. 1 looking in the direction of the little arrows at the ends of the section-lines. Fig. 3 is a detail view of a

slightly-modified form, the same being taken through the end of one of the pillars on a line corresponding to line 2 2 of Fig. 1.

In the drawings similar letters of reference refer to similar parts throughout the several views.

Referring to the lettered parts of the drawings, the reel-frame is made up of heads connected together by suitable pillars B B'. The heads are laminated, consisting of outer metallic side plates A and inner metallic rings a, between which are rings A', preferably of rubber, hard fiber, or similar equivalent material. These rings and side plates are perforated, and extending through the same are the ends of the pillars B, suitably shouldered to receive and retain the same. The pillars B are bored out at their right-hand ends and suitably screw-threaded and receive screws e, which securely clamp the rings and plate A at that end thereto on the shouldered end of the pillar. The left-hand ends of the pillars B are shouldered and the ends are screw-threaded, entering screw-threaded holes in the plate A, rubber ring A' and metallic ring a at that end, clamping those parts securely together. The ends of the screws project flush with the surface. The pillars B', to which the reel-plate is secured, are counterbored at both ends and receive small screws for clamping the laminated structure thereon, clamping the same at the shoulders, as before stated. Intermediate pillars, of course, can extend up to the heads at each side and be retained by the long screws through the plates and rings entering their ends. Only sufficient pillars need be shouldered to properly locate the parts. By this construction, the hardened bearings for the spool-journals may be screw-threaded into the centers of the plates A, and the reel can be removed as soon as the end plate A is detached, thereby avoiding the necessity of entirely disassembling the parts.

The spool C is provided with journals at each end of different size, the smaller one being at the left, thus making it necessary that the parts be assembled correctly, as, owing to the formation of the parts, the plate A is the last piece to be put into the case or frame. By this formation the flanges C' C' of the spool can extend into the recessed head and be thereby protected, and the necessity of fitting one flat surface—namely, the spool-flange—accurately against another—namely, the frame-head or side plate—which is now the common practice in the manufacture of reels, is

avoided, and consequently liability to friction is overcome. This reel runs freely, even though the casing may be slightly deflected owing to uneven expansion under heat or being slightly inaccurate in its formation. The bearings at each end retain the spool in substantially the central position.

The crank-handle E' of this reel is provided with a metallic bearing f', which embraces the spindle f within the handle and is flanged outwardly to form a washer at the point of contact of the handle with the crank, there providing an effective and durable handle, as clearly appears in the illustration at Fig. 2.

15 By broadening the laminated structure—namely, a metallic ring, a ring of hard rubber or similar like material, and a metallic end plate—a structure of reel-frame is secured having substantially all the advantages of the frame with the rubber heads in that the necessary size is secured with a minimum weight, it being desirable to have these structures as light as possible consistent with the desired strength. The metal arranged in this way, 20 in connection with the hard rubber or fiber, prevents the warping of the rubber, consequently overcoming that objection and securing the advantages of the rubber heads without the disadvantages. This arrangement, 25 however—namely, of an inner ring, an outer plate, and an intermediate broad ring to secure the necessary space for the introduction of the reel mechanism—is desirable where the intermediate ring marked on the drawings 30 is of metal, as is clearly illustrated in Fig. 3, where a light ring of metal is substituted for the ring of rubber. This, however, is not so nearly satisfactory as the rubber clamped between the parts.

40 By the structure of this patent a superior finish is obtained to the reels, because there is no strain or warping of the metal entering into the sides and side rings to form caps. The same being cut into perfectly flat disks and 45 rings is not marred or abraded, and consequently can be finished in a more satisfactory manner. Such a structure is obviously more satisfactory and economical to produce. By working the different parts in the flat it is 50 also obvious that they can be much more readily and satisfactorily fitted together, it being obvious that the flat surfaces will readily conform to each other when clamped by the screws, whereas if there was cut formation 55 they would not so readily yield and would require a much more careful fitting of the parts.

Having thus described the invention, what is claimed as new, and desired to be secured by Letters Patent, is—

60 1. In a fishing-reel frame, the combination of the suitable pillars shouldered at each end; heads made up of metallic rings embracing

the reduced ends of the pillars and resting against the shoulders; hard-rubber rings embracing the extension and fitting against the 65 metallic rings; and flat metallic plates to the outside clamped upon the rubber rings by suitable screws, engaging the reduced ends of the pillars, for the purpose specified.

2. In a fishing-reel, the combination of suitable pillars; heads made up of inner metallic rings; hard-rubber rings adjacent thereto; and flat side plates clamped against the pillars, for the purpose specified.

3. In a fishing-reel frame, the combination 75 of suitable pillars; a head made up of an inner metallic ring resting against the pillars; an outer plate and an intermediate ring separating the plate from the inner ring to form a suitable chamber for the reel-actuating mechanism and to receive the flange of the spool, for the purpose specified.

4. In a fishing-reel frame, the combination of suitable pillars; a head made up of an inner metallic ring resting against the pillars; 85 and a hard-rubber ring clamped against the metal ring, for the purpose specified.

5. In a fishing-reel frame, the combination of the pillars and a head comprising a rubber ring forming a chamber and a flat side plate 90 clamped upon the ring and extending to the full diameter of the head for the protection of the rubber, as specified.

6. In a fishing-reel frame, the combination 95 of pillars; and a head, comprising an inner metallic plate, an outer metallic plate, and an intermediate body of rubber chambered to receive the operating mechanism, arranged between said plates, as specified.

7. In a fishing-reel frame, the combination 100 of pillars; and a head comprising an inner metallic plate, an outer metallic plate, and an intermediate body of rubber clamped between said plates, as specified.

8. In a fishing-reel frame, the combination 105 of pillars; and a head, comprising an inner metallic plate, an outer metallic plate, and an intermediate body of rubber arranged between said plates, as specified.

9. In a fishing-reel frame the combination 110 of suitable pillars having shoulders thereon; a ring having holes therein arranged to receive said pillars and rest against said shoulders, said ring serving as a support for said pillars; and an outer structure, chambered to receive 115 the reel-operating mechanism, secured in place on the projecting ends of said pillars, for the purpose specified.

In witness whereof I have hereunto set my hand and seal in the presence of two witnesses.
